BOILER

Thomas C. Ervin, Chattanooga, Tenn.

Application February 5, 1935, Serial No. 5,013

3 Claims. (Cl. 122—369)

This invention relates to the firebox structure of steam boilers.

Important objects of the invention are to attain a more rapid and uniform heat transfer from the firebox to the water within the boiler, to eliminate leaks and other possible faults occasioned by overheating of sheets, burned rivets and the like, to accomplish these results and at the same time reinforce and strengthen the firebox, to simplify and improve the mud ring, to provide a more effective distribution of the water about the firebox sheet and to locate the manhole and steam dome in more effective relation.

15 The foregoing and other desirable objects are attained in the present invention by the novel features of construction, combinations, relations and arrangements of parts as hereinafter set forth, illustrated in the accompanying drawings and broadly covered in the claims annexed.

20 The attached drawings illustrate one practical commercial embodiment of the invention, but it will be appreciated that changes and modifications in structure may be made all within the true intent and broad scope of the invention.

25 Fig. 1 is a broken longitudinal sectional view of an oil field boiler having features of the invention incorporated therein.

Fig. 2 is a broken part sectional and part end 30 elevation of the boiler.

Fig. 3 is an enlarged broken sectional detail of the single thickness butt welded joint between the firebox sheet and the flange of the firebox door head showing the rows of supporting stay bolts at opposite sides of said weld, as on line 35 3—3 of Fig. 2.

Figs. 4, 5, 6 are broken sectional details illustrating successive stages in the mud ring structure.

40 Figs. 7, 8, 9, are further broken part sectional details of the mud ring, Fig. 7 showing this structure as viewed from the rear, Fig. 8 as viewed from the side looking in the direction of arrow 8, Fig. 7 and Fig. 9 a horizontal section as on line 45 9—9 of Fig. 7.

As shown particularly in Fig. 1, the firebox flue head 10, and the firebox door head 11, are made up with inwardly facing edge flanges 12, 13, opposed to and aligned with the opposite edges of the crown sheet or firebox sheet 14, and these parts are integrally united in such aligned relation by butt welds 15, 16.

At opposite sides of the welds 15, 16, and closely adjoining the same are the rows of stay bolts 50 17, 18, extending between flanges 12, 13, and

the surrounding wagon top wrapper sheet 19, and 20, 21, between the firebox sheet 14 and the wagon top wrapper sheet.

These rows of stay bolts at opposite sides of and close to the welds relieve the welds of stresses 5 and amply carry the load.

In the illustration, the two welds are on straight, parallel lines, extending up the sides and across the crown of the firebox. These welds are therefore readily accomplished, but particular 10 care is taken in making them. Thus for example, as indicated in Fig. 3, the edges of the head flanges and firebox sheet are chipped to remove any fractured or burned metal and are lined up with an approximately 70° angle to be 15 filled in by the weld. Starting at the fire side, the weld is laid in bead-by-bead and each layer is thoroughly cleaned before the next layer is put on. After this, the opposite or water side is gouged and then welded up smoothly in the 20 same fashion as indicated at 16a.

This construction provides a firebox wall of uniform thickness and free of any uneven transmission of heat, such as necessarily present with lapped sheets and rivets extending therethrough 25 as heretofore practiced. As a consequence, overheating of sheets and the burning of rivets and leaks resulting therefrom are entirely eliminated.

Also, as a result of the uniform and more efficient heat transmission, it is possible to develop 30 a higher power rating at a usual or customary rate of firing.

With this butt weld construction, the head flanges and firebox sheet are of the same diameter. As a consequence, the flame flow is more 35 regular and smooth. The diameter being the same at both sides of the welds, the supporting and reinforcing stay bolts at opposite sides may be of the same length.

This feature of unitary, thoroughly reinforced 40 structure is carried out in the mud ring as illustrated particularly in Figs. 4, 5 and 6, by using a solid ring 22, drilled for staybolt openings 23, and having the inner and outer boiler sheets 14, 19, drilled with smaller registering openings 24, 45 Fig. 4, which then while carefully held are reamed to the same diameter as in Fig. 5, after which both sheets and mud ring are tapped as at 25, Fig. 6, to take the screw-threaded staybolts 26, which latter are headed at 27.

50 Care is taken to remove burrs or anything that might prevent the boiler sheets from laying up closely against the sides of the mud ring and the sheets are bolted or clamped tightly in place against the mud ring when the three parts, that 55

is, the mud ring and the sheets at opposite sides are tapped, so that the staybolts will screw into position holding the parts in this relation.

The heading, riveting or upsetting causes the 5 end portions of the staybolts to swell or expand in the threaded holes of the boiler sheets and mud ring and effects a longitudinal compression causing the bolts to draw the sheets in tightly against the mud ring. The staybolts are thus 10 sealed to the boiler sheets and mud ring and the boiler sheets are tightly sealed to the mud ring. As a precaution against expansion leaks, the edges of the sheets may be caulked and welded to the mud ring as indicated at 28.

15 The back sheet or head 29 is shown as flanged inside the wagon top wrapper at 30, Fig. 1, and Fig. 9 shows that where this flange meets the mud ring it seats within a recess or shouldered portion 31, in the corner of the mud ring, with 20 the wrapper sheetlapping it at this point. These outside corner portions as indicated in the latter view, may be held by shorter staybolts 32, screw-threaded in through the outer sheets and mud ring and headed over at the outside in the same 25 manner as the through staybolts 26.

Thus the entire inside of the firebox presents a relatively smooth surface, free of rivet heads. Also, extra long rivets, such as heretofore used for securing mud rings are avoided. With such 30 long rivets, it has not been possible heretofore to entirely plug the holes in the mud ring or boiler sheets, but with staybolts screw-threaded into both the sheets and the ring and headed at both ends, the holes in the joined parts are completely closed and the sheets drawn together 35 against the ring.

In Fig. 2, the sides of the firebox sheet are shown at 33, inclined inwardly toward the top, so as, with the substantially parallel sides 34 of the wagon top wrapper sheet, to provide water 40 spaces 35, at the sides of the firebox, gradually widening toward the top. This accelerates water circulation at the sides and over the top of the firebox and the inward slopes of the firebox sheet present more effective heat absorption surfaces 45 to the fire.

The dome 36 is indicated in Fig. 1, as located on the middle course 37, of the boiler, as far forward from the firebox as practicable. This 50 gives the wet steam coming over from the firebox the more opportunity to dry out or lose moisture before entering the dome.

A manhole is indicated at 38, Fig. 1, in the top of the boiler shell back of the dome, that is, between the latter and the back head and as close 55 as possible over the firebox tube head, where washing and removing of scale is most difficult.

With the solid unitary construction disclosed, the firebox may be built to greater length with 60 safety, to provide a better ratio of furnace volume

to heating surface. Improved generation of steam is thus made possible as will be realized when it is considered that approximately 60% of the water is evaporated over and around the firebox. The entire surface exposed to the fire is of uniform thickness. There is thus no uneven transmission of heat, such as occasioned by lapped sheets and rivet heads. Overheating, leaking and burned rivets are thus eliminated and with the same firing a much greater power output is 10 attained.

What is claimed is:

1. A mud ring structure, comprising outer and inner boiler sheets, a mud ring between said sheets, said sheets and intermediate mud ring 15 having aligned tapped openings therethrough, staybolts screwed in said tapped openings through said outer and inner boiler sheets and mud ring, the ends of said staybolts being upset and expanded into the screw threads in said 20 boiler sheets and mud ring, thereby entirely plugging the same and being compressed longitudinally to bind the boiler sheets against the sides of the mud ring.

2. The herein disclosed method of boiler manufacture, which comprises drilling a mud ring with staybolt openings, drilling outer and inner boiler sheets with smaller registering openings and while holding said sheets closely against opposite 25 faces of the mud ring, reaming said registered sheet and mud ring openings to the same diameter and screw-threading through all three held parts, screwing staybolts through said 30 threaded openings in the outer and inner boiler sheets and intermediate mud ring while the parts 35 are so held and then upsetting the ends of said staybolts to thereby completely plug the screw-threaded openings in mud ring and boiler sheets and bind the boiler sheets against the opposite faces of the mud ring. 40

3. The herein disclosed method of boiler manufacture, which comprises drilling a mud ring with staybolt openings, drilling outer and inner boiler sheets with smaller registering openings and while holding said sheets closely against opposite 45 faces of the mud ring, reaming said registered sheet and mud ring openings to the same diameter and screw-threading through all three held parts, screwing staybolts through said 50 threaded openings in the outer and inner boiler sheets and intermediate mud ring while the parts are so held and then upsetting the ends of said staybolts to thereby completely plug the screw-threaded openings in mud ring and boiler sheets and bind the boiler sheets against the opposite 55 faces of the mud ring and caulking and welding the edges of the boiler sheets to the opposite faces of the mud ring below the headed staybolts as a precaution against expansion leaks.

THOMAS C. ERVIN. 60
